Primary Examiner — Barbara Fox*Assistant Examiner* — Dana K Weiland(74) *Attorney, Agent, or Firm* — Birch, Stewart, Kolasch & Birch, LLP(57) **CLAIM**

The ornamental design for a display screen with graphical user interface, as shown and described.

DESCRIPTION

The FIGURE is a front view of a display screen with graphical user interface showing our new design.

The broken lines shown in the drawings represent portions of the display screen with graphical user interface that form no part of the claimed design. The dash-dot broken lines define the bounds of the claimed design and form no part thereof.
